ATTORNEYS

UNITED STATES PATENT OFFICE.

JOHN H. SUNDERMAN, OF QUINCY, ILLINOIS.

WHIP-SOCKET.

SPECIFICATION forming part of Letters Patent No. 224,241, dated February 3, 1880.

Application filed July 19, 1879.

To all whom it may concern:

Be it known that I, JOHN H. SUNDERMAN, of Quincy, in the county of Adams and State of Illinois, have invented certain new and useful Improvements in Whip-Sockets; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a perspective view of my whip-socket, and Fig. 2 is a side elevation of the same.

My invention relates to whip-sockets; and it consists in certain peculiarities of construction, as will be hereinafter more fully set forth, and pointed out in the claim.

The annexed drawings, to which reference is made, fully illustrate my invention.

A represents the main or stationary part of the whip-socket, made in skeleton form, and cast with three brackets, *a b d*, on the back. The bracket *b* has a slot at *x*, and is threaded at *y* for the attachment of the fastening *B*; which consists simply of a short metal strap having a headed pin or rivet, *i*, at one end. This pin or rivet is slipped into the slot *x*, and a screw, *h*, is passed through the other end of the strap and screwed into the part *y* of the bracket.

The part *A* of the socket is made of the curved form shown, bent in at top and bottom, and with its brackets cast all in one piece.

35
C is the short piece of the whip-socket, cast, pressed, or stamped in proper shape, and hinged or jointed at both sides to the main part *A*. It is also hinged or riveted at the bottom, as shown.

40
This whip-socket will hold a large or a small whip without rattling or letting it through the sides or bottom. The whip will have three bearings, *m*, and will be held tight and straight. It will also be noticed that the 45 socket is a little wider in the middle, where the butt of the whip goes in.

I claim—

The within-described whip-socket consisting of the stationary part *A*, cast with the three 50 brackets *a b d*, the strap *B*, and short piece *C*, all constructed and joined together substantially as herein set forth.

In testimony that I claim the above I have hereunto subscribed my name in the presence 55 of two witnesses.

JOHN H. SUNDERMAN.

Witnesses:

RICHARD JANSEN,
H. H. JANSEN.
